UNITED STATES PATENT OFFICE.

WALTER G. BURNS, OF FORT WAYNE, INDIANA.

GRADE-CROSSING SIGNAL.

Application filed September 14, 1923. Serial No. 662,668.

To all whom it may concern:

Be it known that I, WALTER G. BURNS, a citizen of the United States of America, and resident of Fort Wayne, in the county of 5 Allen and State of Indiana, have invented new and useful Improvements in Grade-Crossing Signals, of which the following is a specification.

This invention relates to improvements in 10 grade crossing signals and the object thereof is to provide permanent signs along the roadside at approaches to railways, and to construct the signs in such manner that they will be plainly indicative of a railway, and 15 so that the characteristic appearance thereof will be maintained throughout ordinary climatic variations.

It has been the custom to place signs of 20 various shapes at road approaches to grade crossings, and upon which legends are painted, such as "Railway Crossing," "R. R.," etc., which lettering frequently becomes obscured in inclement weather and from accumulations of dust. And, when such signs 25 become coated with snow, their purpose is not plainly apparent and are therefore objectionable. The present invention contemplates a remedy for such objections and is included as an object of the improvement.

30 These objects are accomplished by the construction illustrated in the accompanying drawings, in which:—

Fig. 1 is an elevation of a construction embodying the invention and showing the 35 front exposure thereof;

Fig. 2 is a plan view projected from Fig. 1; and

Fig. 3 is a side elevation showing the manner of mounting the sign on a post.

40 The characters appearing in the description refer to parts shown in the drawings and designated thereon by corresponding characters.

45 The invention comprises a sign formed of a pair of flat-faced bars 1 spaced apart and horizontally disposed, and a series of vertically disposed bars 2 spaced apart, the vertical bars being secured to the backs of the horizontal bars with their respective ends 50 projecting beyond the corresponding horizontal bars. Also, the respective ends of the horizontal bars project outwardly beyond the series of vertical bars, the arrangement of the horizontal and vertical bars simulating in outline a fragmentary section of a 55 structure of railway rails and ties.

The sign thus formed is mounted in connection with a post 3, preferably with space-blocks 4 inserted between the post and the sign so that the sign will appear in bold 60 relief when viewed from its front exposure, with the post as part of the background. A pair of braces 5 are secured to the post at their middles and with their respective ends in supporting connection with the sign. By 65 painting the post a dark shade and enameling the sign white, or applying luminous white paint thereto, the sign becomes very conspicuous and affords an exceedingly efficient signal for grade crossings. 70

If so desired, duplicate signs may be placed upon the post, with the additional sign beneath the other, and spaced apart therefrom, as indicative of their being more than one track at the grade crossing. This 75 feature, however, is not illustrated in the drawings.

What I claim is:—

1. In a signal for grade crossings, a sign 80 formed of a pair of horizontally disposed flat-faced bars spaced apart, and a series of vertically disposed flat-faced bars spaced apart, the vertical bars being secured to the backs of and intersecting the horizontal bars with their respective ends projecting beyond 85 the corresponding horizontal bars, and the respective ends of the horizontal bars projecting beyond the series of vertical bars; a mount to which the sign is secured, said mount including a post, there being space-blocks intervening between the sign and post; and braces secured at their middles to the post on the side thereof opposite the sign, and with their ends in supported connection with the sign. 90

2. In a signal for grade crossings, a sign 95 formed of a pair of horizontally disposed flat-faced bars spaced apart, and a series of vertically disposed flat-faced bars, spaced apart and respectively secured to the backs 100 of the horizontal bars with their respective ends projecting beyond the corresponding horizontal bars, the respective ends of the horizontal bars extending beyond the series of vertical bars; and means holding the sign 105 in supported relation with the post in a vertical plane apart from the post.

3. A signal for grade crossings comprising a configuration constructed of flat-faced bars 110 simulative of a fragmentary section of a structure of railways rails and ties, and a mount therefor including a post and means

for holding the configuration in a vertical plane aside from the post.

4. A grade crossing sign consisting of a structure of horizontal and vertical flat-faced bars spaced apart in simulative arrangement of a fragment of a railway track and supported in a vertical plane.

5. A sign for a grade crossing consisting of a configuration constructed of spaced intersecting flat-faced bars, both ends of which

extend outwardly beyond the respective intersecting bars and simulating a fragmentary section of railway track.

In testimony whereof I affix my signature in presence of two witnesses.

WALTER G. BURNS.
